UNITED STATES PATENT OFFICE.

MAURICE J. ROTHSCHILD, OF NEW YORK, N. Y., ASSIGNOR TO ROTHSCHILD-SEAMAN COMPANY, OF MILWAUKEE, WISCONSIN, A CORPORATION OF WISCONSIN.

DESIGN FOR AN AUTOMOBILE-BODY.

43,679.

Specification for Design.

Patented Mar. 4, 1913.

Application filed January 20, 1913. Serial No. 743,213. Term of patent 3½ years.

To all whom it may concern:

Be it known that I, MAURICE J. ROTHSCHILD, a citizen of France, residing in New York, in the county of New York and State of New York, have invented a new, original, and ornamental Design for an Automobile-Body, of which the following is a specification, reference being had to the accompanying drawing, forming a part thereof.

The figure is a perspective view of an automobile body showing my new design.

I claim:

The ornamental design for an automobile body as shown.

MAURICE J. ROTHSCHILD.
